UNITED STATES PATENT OFFICE.

CLARENCE A. MICHEL, OF CLEVELAND, OHIO, ASSIGNOR TO THE GUIDE MOTOR LAMP MANUFACTURING COMPANY, OF CLEVELAND, OHIO, A CORPORATION OF OHIO.

AUTOMOBILE HEADLIGHT.

Application filed February 7, 1925. Serial No. 7,441.

This invention relates generally to automobile headlights and more particularly to a novel construction of reflector adapted for use in connection with an incandescent lamp having two independently operable lighting filaments.

At the present time all automobile headlights are constructed with the idea of eliminating the disagreeable glare when approaching another automobile. This has been accomplished to a certain extent by modifying the reflector in order to compensate for the commercial filament. It is also accomplished sometimes by the peculiar construction of the headlight lens and in some instances by the use of a lens in connection with a modified form of reflector.

The prime object in road illumination is to have the top of the beam at the proper legal height and at the same time carried as far forward as possible and in some instances lateral spread has been obtained by the use of prismatic lenses and also fluted reflectors. Furthermore, in most of the automobile headlights there are two incandescent lamps employed, one at the center which is usually of greater candle power than the second one, which is arranged near the top of the reflector. The center light is intended for road driving whereas the upper light known as the dimmer is intended for city driving or for use in passing another automobile.

The object of my invention is to employ a single lamp having two filaments, this lamp being arranged at the center of the reflector and another feature of my invention consists in constructing this reflector so that one filament can be used for road driving and the second filament for city driving or for use when passing another automobile, inasmuch as the reflector is so constructed as to direct or bend downwardly the top portion of the beam so that all possibility of glare is eliminated. Broadly speaking, this control of the light is accomplished by correcting the upper part of the upper half of the reflector and the lower part of the lower half of the reflector and more specifically stated these corrections are made by the modification of the two parabolic sections, the tilting of the sections downwardly, the use of a modifying lens, or the wider separation of the focal points of the sections of the parabola, or any combination of the specific corrections hereinbefore mentioned.

Having described the broad conception of my invention, I shall now describe one form of the reflector in connection with one form of filament and whereby the scope of my invention is accomplished.

In the drawings forming part of this specification, Fig. 1 is a vertical sectional view of my improved form of reflector with lamp arranged therein and Fig. 2 is a face view of the reflector.

Referring to the drawings A indicates an incandescent lamp having two independently lighted filaments B and C, the filament B being placed very slightly below the axis of the reflector and the filament C approximately $\frac{3}{2}$ of an inch below the filament B. The filaments B and C have some lineal dimension and in practice it is preferred that the upper half of the reflector will have its focus substantially in vertical alignment with the rear end of the filament and the lower half of the reflector preferably has its focal point in vertical alignment with the forward ends of the filaments. The upper half of the reflector, however, is tilted forwardly, the amount of the tilt being indicated by the full line F G whereas the curvature of revolution without the tilt is indicated by the line F G'. The tilting of the axis is indicated by the dotted line X—X in Fig. 1 passing through the filament B. This downward tilt of the upper half of the reflector will insure the downward direction of the rays of light emanating from either filament. The forward and lower portion of the lower half of the reflector is also tilted downwardly as indicated by the line H I whereas the untilted curvature of revolution is indicated by the line H I'. This downward tilting of the lower portion of the lower half of the reflector is to insure the downward direction of all the rays emanating from either filament and reflected by the lower portion of the reflector. In order to avoid formation of sharp angles by the intersection of curvatures of different revolutions and also to facilitate the manufacturing of the one piece reflector I provide transition surfaces K between the upper and lower halves of the reflector and transition surfaces L between the sections of the lower half of the reflector.

- In operation, the lower filament C is employed as the main or driving light and when lighted the beam of light will be projected forwardly a considerable distance and all of the rays will be horizontal and slightly below the horizontal. When the lower filament C is cut out and the upper filament B cut in the rays will be still further depressed thereby rendering the lamp particularly safe
- 5 10 15 20 25 30
- for street illumination or for passing other vehicles inasmuch as the disagreeable glare is entirely eliminated even though the road be uneven and the lamp subject to a slight rocking motion.
- Although I have not shown any special construction of headlight lens arranged in front of this reflector, it is obvious that a plain lens could be employed and the reflector fluted or any suitable form of modified lens could be employed for the purpose of giving lateral distribution or spread to the controlled rays emanating from the reflector.
- Having thus described my invention, what I claim is:—
1. In a light projector, the combination with an incandescent lamp having two independently lighted filaments and a reflector, one of said filaments being located slightly below the axis of the reflector and the second
- filament below the first named filament, the upper half of the reflector being parabolic, the axis of said section being tilted downwardly, the lower section of the reflector being parabolic with the lower forward portion thereof tilted downwardly and whereby all of the rays from either filament will be reflected downwardly.
2. In a light projector, the combination with a reflector and an incandescent lamp having two independently lighted filaments, the upper filament being located slightly below the axis of the reflector, the lower filament being located below the first named filament, the upper half of the reflector being parabolic, the axis thereof being tilted downwardly, the rear portion of the lower half of the reflector being parabolic, the forward portion of the said lower half of the reflector being a curvature of revolution the axis of which is tilted downwardly whereby the rays of light from either filament will be reflected downwardly and transition surfaces interposed between the upper and lower halves of the reflector and between the front and rear sections of the lower half of the reflector.
- 35 40 45 50 55
- In testimony whereof, I hereunto affix my signature.

CLARENCE A. MICHEL.
